UNITED STATES PATENT OFFICE.

JOHN L. BROWN, OF BOSTON, MASSACHUSETTS, ASSIGNOR TO HIMSELF,
MOSES J. GRODJINSKI, AND EDWARD G. SALTZMAN, OF SAME PLACE.

DESIGN FOR CHILDREN'S CARRIAGES.

Specification forming part of Design No. 7,084, dated January 6, 1874; application filed September 29, 1873.
[Term of Patent 7 years.]

To all whom it may concern:

Be it known that I, JOHN L. BROWN, of Boston, in the county of Suffolk and State of Massachusetts, have invented and produced a new and original Design for the Body and Standard Supporting the Top of a Child's Carriage, of which the following is a full, clear, and exact description, reference being had to the accompanying photograph making part of this specification.

In the photograph, A represents the body of a child's carriage, composed of the several portions, *a b c d e*, having the edges thereof in lines inclined to each other at angles greater than ninety degrees. Thus, the line 5 6 of the back forms an obtuse angle with the line 6 7 of the seat; the line 6 7 a similar angle with the line 7 8, extending from the front of the seat to the rear of the floor; the line 7 8 forms a similar angle with the line 8 9 of the floor; and the line 8 9 of the floor also an obtuse

angle with the line 9 10 of the foot-rest or front of the body, the design thus produced being unique and ornamental.

The distinctive character of my design is found in the lines and angles in the construction of the body of the carriage, and in the curved bifurcated standard supporting the central section of the top, the whole forming a unique and beautiful design.

What I claim as my invention, and desire to secure by Letters Patent, is—

The design for the body of a child's carriage, consisting essentially of the body, having its edges formed with lines and angles, substantially as shown and described.

Witness my hand this 15th day of September, A. D. 1873.

JOHN L. BROWN.
